FREDERICK H. PERRY, OF BEVERLY, MASSACHUSETTS, ASSIGNOR TO UNITED SHOE MACHINERY COMPANY, OF PATERSON, NEW JERSEY, A CORPORATION OF NEW JERSEY.

IMPLEMENT FOR INSERTING MALLEABLE MATERIAL INTO THE FACES OF TOOLS.

1,202,308.

Specification of Letters Patent. Patented Oct. 24, 1916.

Application filed May 26, 1915. Serial No. 30,685.

To all whom it may concern:

Be it known that I, FREDERICK H. PERRY, a citizen of the United States, residing at Beverly, in the county of Essex and State 5 of Massachusetts, have invented certain new and useful Improvements in Implements for Inserting Malleable Material into the Faces of Tools; and I do hereby declare the following to be a full, clear, and exact description of the invention, such as will enable others skilled in the art to which it appertains to make and use the same.

This invention relates to an implement for inserting malleable material in tools, and 15 more particularly to an implement for inserting brasses in the feed points of machines for rough rounding the outsoles of shoes.

In the manufacture of shoes, the outsole, 20 after it has been attached temporarily to the bottom of the shoe, is trimmed to approximately its finished shape to prepare it for the stitching operation. The machine for trimming the outsole, commercially known 25 as the "Goodyear universal rounding and channeling machine", has a tool or feed point which works between the welt and upper to feed the shoe, and also acts as a cutting block for the rounding knife. The 30 feed point is provided with a strip of malleable material such as brass, lead or leather, which is placed in the slot located in the cutting area of the rounding knife. The 35 continued chopping action of the rounding knife serves to wear the malleable material away so that it is necessary to replace the malleable material quite frequently. Heretofore it has been the practice to replace the 40 malleable material in the cutting slot of the feed point by driving the material into the slot by means of a hammer. With the hammering operation, it was difficult to get the malleable material securely fastened in position. The action of the hammer injured 45 the face of the tool, and often resulted in breaking the tool. The hammering method of driving brasses into feed points, further consumes a large amount of time of the operative.

50 The primary object of the present invention is to provide an implement which will overcome the objections referred to, and by which malleable or other material may be

quickly and securely inserted in feed points or other tools.

In accordance with this object, one feature of the invention contemplates the provision in an implement for inserting malleable materials in tools, of means for holding and supporting the tool, and a pressure jaw 60 for forcing the material into the face of the tool when supported. This and other features of the invention relating to certain devices, combinations and arrangements of parts hereinafter described and claimed, will 65 be understood from an inspection of the accompanying drawings, and the following detailed description of the construction illustrated therein.

In the drawings, Figure 1 is a perspective 70 view of an implement embodying the invention in its preferred form; Fig. 2 is a vertical section of the implement taken on the line 2—2 of Fig. 1; and Fig. 3 is a plan view of the feed point of a Goodyear universal rounding and channeling machine.

The invention is shown as embodied in an implement designed for pressing brasses into the feed points of the rounding and channeling machine above referred to. This 80 implement comprises in general a base for supporting and holding the feed point, and a pressing lever by which the brasses are forced into the cutting slot of the feed point. The base 10 is provided with an anvil 12 for supporting the beveled end of a feed point, and a table 14 for supporting the rear end of the feed point. An adjusting screw 16 is mounted in an abutment 18 formed integral with the base 10 in a position to engage the rear end of the feed point. This adjusting screw serves to position the feed point on the anvil and table 14, and also acts as an abutment to retain the feed point in position, and to receive 95 the end thrust of the feed point during the pressing operation. The anvil 12 is constructed of hardened steel or similar material, and is held in place in a slot 20 in the base 10 by means of a screw 22. The working face of the anvil is inclined to correspond to the bevel of the feed point so that when a feed point 24 is in position on the anvil and table 14 ready for the insertion of a brass, its inclined face 26 will exactly 100 register with the face of the anvil. The

pressing lever 28 is pivotally mounted in the base 10, and has a pressing jaw 30 and a gage stop 32. The pressing jaw 30 is constructed of hardened material, and is adapted to move over the anvil in the area occupied by the cutting slot 34 of the feed point when it is in position on the base. The gage stop 32 is located in a position to engage the abutment lug 18 when the pressing lever 10 is brought down without any feed point in place.

As shown in Fig. 1, a strip of brass 36 is placed in position over the cutting slot 34, ready to be forced in by the pressing jaw 30. The brass strip has the same length as the slot 34, and is slightly wider than the slot 34, so that when the brass is forced into the slot 34, it will be securely fastened in position. These strips of brass can be 20 prepared the same length as the slot 34, and may be quickly inserted into the slot without waste of material.

In the machine illustrated in the drawings, the base 10 is cast integral with a 25 handle 38 and an attaching flange 40. The attaching flange is used for mounting the implement on a pedestal or bench to locate it in a convenient position for the operator, and the handle 38 is adapted to be 30 used in coöperation with the pressing lever 28 while forcing the brass into the feed points. In some cases it may be preferable to omit the attaching flange 40 and use the implement as a bench tool.

35 With the above construction the brasses may be quickly and securely inserted in the feed points without loss of material, and without danger of injury to the brass or feed point.

40 While brass forms an excellent malleable material against which the rough rounding knife may cut, other malleable material, such as lead, copper, etc., may be used, and may be inserted by the above described implement. The implement is also well adapted for pressing strips of leather or other fibrous material into the cutting slots of tools or other implements. The anvil 45 12 may be variously modified for supporting 50 different types of tools.

The nature and scope of the invention having been indicated, and the preferred embodiment of the invention having been specifically described, what is claimed as 55 new is:—

1. An implement for inserting malleable material into the faces of tools, having, in combination, a base, an anvil having an in-

clined face for rigidly supporting a tool, an abutment on the base opposite the face 60 to engage the tool and receive the end thrust of the tool due to movement on the anvil, and a pressure jaw movable to and upon the portion of the tool supported on the anvil. 65

2. An implement for inserting malleable material into the faces of tools, having, in combination, a base, having an anvil for supporting the tool and an adjustable abutment for positioning the tool, and a pressing 70 lever having a jaw movable to press upon the portion of the tool supported on said anvil to insert malleable material into the tool.

3. An implement for inserting malleable 75 material into the faces of tools, having, in combination, a supporting lever, an anvil on the lever for supporting the tool, an abutment on the lever to engage the tool and hold it from movement on the anvil, 80 and a pressure lever pivotally connected to the supporting lever and having a jaw for pressing against the portion of the tool supported on the anvil, the faces of the anvil and the pressing jaw being angularly 85 arranged when the pressure lever is in operation upon the tool.

4. An implement for inserting malleable material into the faces of tools, having, in combination, a base for supporting a feed 90 point having an anvil with an inclined face to support the beveled end of the feed point, an abutment for engaging the opposite end of the feed point, and a pressure jaw for co-operating with the anvil for pressing a brass 95 into a slot in the face of the feed point.

5. An implement for inserting malleable material into the faces of tools, having, in combination, a base for supporting a feed 100 point having an anvil with an inclined face 105 to support the beveled end of the feed point, an abutment screw for engaging the other end of the feed point, a pressing lever pivoted on the base and having a pressure jaw for co-operating with the anvil, and a stop for limiting its movement toward the base.

6. An implement for inserting brasses in feed points, having, in combination, a base for supporting a feed point having an anvil with an inclined face to support the beveled 110 end of the feed point, and an adjusting screw for positioning the feed point and a pressing lever pivoted to the base, having a jaw movable over the anvil for forcing brasses into a cutting slot of the feed point. 115

FREDERICK H. PERRY.
